LLP; Robert J. Ward

(51) LOC (10) Cl. 14-01

CLAIM

(52) U.S. Cl.

The ornamental design for a dual push-to-talk radio microphone, as shown and described.

USPC D14/226; D14/137

DESCRIPTION

(58) **Field of Classification Search**

CPC H04R 1/08; H04R 11/04; H04R 25/04;
H04R 25/65

USPC D14/225, 110, 155, 158, 159, 137, 185,
D14/186, 188, 191, 204, 210, 212, 214-219,
D14/221, 226, 228, 229, 240, 416;
D21/329, 483; D13/168; 379/368, 430,
379/431, 433, 433.02, 388, 419, 420, 428,
379/440, 441, 442, 426, 454, 455; 381/91,
381/122, 355, 357, 358, 163, 191, 153, 157,
381/161, 361; 455/77, 78, 90, 90.1, 90.3,
455/550, 151.1, 158.2, 575, 575.1, 575.2,
455/575.8; 446/410, 454; 181/158, 242;
D10/106.1

FIG. 1 is a perspective view of a dual push-to-talk radio microphone;

FIG. 2 is a top view of the dual push-to-talk radio microphone;

FIG. 3 is a bottom view of the dual push-to-talk radio microphone;

FIG. 4 is a left side view of the dual push-to-talk radio microphone;

FIG. 5 is a front view of the dual push-to-talk radio microphone;

FIG. 6 is a right side view of the dual push-to-talk radio microphone; and,

FIG. 7 is a back view of the dual push-to-talk radio microphone.

The broken lines of FIGS. 1 through 7 are for illustrative purposes only, showing the environment, and form no part of the claimed design.
